HIRAM B. ELY, OF PHILADELPHIA, PENNSYLVANIA

ACOUSTIC HORN

Application filed January 21, 1929. Serial No. 333,927.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

5 The subject of this invention is an acoustic horn especially adapted for a sound locating apparatus.

The range at which a sound locating apparatus is capable of effectively being employed 10 depends upon the intensity of the auditory impression at the small end of the horn and this is governed by the amount of sound energy at the small end compared to the amount of energy entering the mouth of the 15 horn. Sound waves being pressure waves increase in force as they proceed towards the small end of the horn until a certain critical value is reached after which the increase in friction due to attenuation of the horn more 20 than offsets the increase in intensity and the energy diminishes. Accordingly the shape and length of the horn and the dimensions of its small and large ends are factors entering into a determination of its efficiency.

25 The shape of the most efficient type of horn known at present is that in which the cross-sectional area is an exponential function of the distance from the small end of the horn. But in order to obtain the best results the 30 rate of change of cross-sectional area cannot be selected at random but must be determined by a prior consideration of the other dimensional factors. I have discovered that the rate of change should possess such a value 35 that the length of the horn is substantially equal to the wave length of the lowest frequency of sound to be transmitted throughout the horn. With the dimensions of the small and large ends of the horn and the optimum angle of the large end selected, then the selection of the rate of change is determined from the proposition that the wave length fixes the rate of change of cross-section.

45 Extended experiments have shown that the selection of the dimensions of a receiver horn can not be predicated on the dimensions of a radiator horn, if correct intensification and the elimination of reflections are to be se-

cured. This invention, therefore, relates also to the dimensioning of a receiver horn.

Where in order to secure the designated length of a horn it becomes necessary to bend it for convenience of mounting the curvature 55 of the elbows and their positioning with respect to the length of the horn plays an important rôle in transmitting sound waves without interference and in preserving phase relations. Sound waves on entering a horn 60 from the free atmosphere pass through a transitory period of turbulence before the formation of the confined wave takes place. Further, where the large end of the horn is 65 rectangular for the purpose of obtaining directly the point of transition to curvilinear form must be properly located with respect to the length of the horn to avoid non-uniform disturbances.

In arranging horns in pairs for the binaural comparison of sound no attention has heretofore been given to a spacing of the horns to produce a maximum phase difference. Theoretically the greater the separation between horns, the sharper will be the 70 phase effect but I have found in application that this holds true only up to a certain point beyond which incorrect interpretations or impressions are made. The most effective results are obtained when the separation of the 75 horn axes is equal to the wave length of the 80 lowest pitch to be received.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing 85 from the spirit of the invention.

A practical embodiment of the invention is illustrated in the accompanying drawings, wherein:

Fig. 1 is a view in rear elevation of a sound 90 locating apparatus equipped with the improved horns;

Fig. 2 is a view in side elevation thereof;

Fig. 3 is a sectional view of one of the horns;

Fig. 4 is a diagrammatic view of a pair of horns, illustrating the baffling of non-frontal sound waves; and

Fig. 5 is a detail view of one side of the mouth section of a horn.

Referring to the drawings by characters of reference:

There is shown a sound locating apparatus of the "trumpet" type comprising four horns rigidly interconnected in parallel and arranged in two combinations on intersecting base lines, one such combination comprising the horns A—A for determining azimuth, and another comprising the horns B—B for determining elevation. The support sections 5 of the horns A—A are trunnioned in spaced standards 6 secured to a rotatable carriage 7 and the support sections 8 of the horns B—B are connected to the support sections 5 by means of yokes 9. The interconnected horns are rotated in unison about the horizontal axis of the horns A—A by means of an elevating mechanism 10.

The mounting is so arranged that the distance between the axes of reception of opposite horns is not greater than the length of the longest sound waves it is desired to locate. This selection of the separating distance is based on the fact that accurate binaural comparison is only possible when the sound waves are received less than 180° out of phase or in other words when the axis of the sound locating apparatus is pointed very nearly towards the source of sound. If the two horns were separated a distance greater than that specified, the listener might receive adjacent sound waves in such phase relation as to mislead him to believe he was receiving the same wave in his two ears, less than 180° out of phase thus resulting in incorrect pointing of the apparatus.

The horns are substantially alike and, as seen in Figs. 1, 2 and 3, are made in four sections, namely: a mouth section 11, a reverse curve section 12 paralleling the mouth section, the support section 5 for the horn A and 9 for the horn B extending perpendicularly to the curved section and a flexible tube 5 or 8. The sections 11, 12 and 13 are rigid units composed of aluminum of sufficient thickness and density to prevent an absorption of more than 5% of any sound which impinges upon them and of sufficient rigidity to prevent vibratory action by sound energy. The flexible tube section 13 may be extended through a portion 14 of uniform diameter throughout its length for convenience in attachment to a head set 14a.

The horns are each of exponential cross-section, the form of the equation used in determining the design of the horn being $A = Ao e^{mx}$ in which A is the cross-sectional area at any point; Ao is the cross-sectional area at the small end; e is the Napierian base; M is a constant determining the rate of flare;

x is the distance of A along the axis measured from the small end,—providing m is given such a value as to make

$$\frac{A}{P} = \frac{L}{K}$$

70

where L—the wave length of the lowest frequency to be obtained, K—a constant whose value has been found to lie between 3 and 4 for best performance, when the total length 75 of the horn axis lies between $\frac{3}{4}L$ and L.

A practical horn which gives excellent performance in the reception of sound emanating from an airplane having a frequency between 75 and 150 cycles per second possesses the following dimensions. The total length of the horn is 126 inches divided as follows—the mouth section 48 inches, the reverse curve section, the support section and the flexible section, each 26 inches. 80

The selection of the diameter of the small end having been determined after experiments to lie between .625 and 1 inch, the diameter of the large end having likewise been determined to produce the best results when it is approximately one-fourth of the horn length or 30 inches, and where the constant m has a value of .03 for inch units of length, the corresponding increase in cross-sectional area for every two inches will be approximately 6% in order to obtain a horn of the prescribed length and prescribed diameter of the large end. The constant m may have a value between .03 and .07. 95

A horn constructed in accordance with the foregoing values will give to the walls of the mouth of the horn an angle of approximately 30° and this angle has been found to afford the best reception while giving a sufficient field. 100

In bending or curving a horn of great length to reduce its overall dimensions considerable distortion and loss of energy are introduced by the elbows due to the reflections which take place and cause interference of one sound wave with another. I have found by experiment that this condition is reduced to a minimum by maintaining a straight large end section for at least one-third of the total horn length in order to allow the sound to pass the transitory period of turbulence occasioned by entering the horn from the free atmosphere and conform itself to the gradual attenuation of the horn. The radius of the first elbow 15 should therefore be not less than the dimension of the horn section in the plane of the bend. 110

The horn dimension at this point should be small compared with the length of sound waves being transmitted and as a consequence the sound waves will traverse the bend as nearly as possible without interference and phase relations will be maintained. 125

The reverse curve section is formed with an integral web 16 lying in the plane of the 130

curve and attached to the large end section to supply rigidity thereto.

The foregoing considerations enter into the design of a horn irrespective of the shape 5 of the horn in cross-section. Generally acoustic horns are circular in cross-section but the particular problem presented in the 10 location of distant sounds renders it advisable to employ a structure or arrangement 15 which will increase the directivity of the horns by baffling non-frontal sound waves.

Referring particularly to Fig. 1, the mouth 20 section 11 of the horn is rectangular in cross-section, the inner side of each horn when 25 arranged in pairs being constituted by a plane surface 17 and remaining sides being flared to produce reflections that will aid in the location of sound. Of the three flared walls the one 18 opposite the plane wall 17 has a 30 more pronounced curvature which acts in the off horn C of Fig. 4, either to baffle non-frontal sound waves indicated by the arrows b—b and by reflection cause them to pass out of the horn or as indicated by the sound 35 waves c—c to effect their intensity and time of arrival.

The same curvature serves in the near horn 40 D of the illustration to increase its perception and augment the binaural phase effect. 30 The sound waves a—a approaching the horn in a plane perpendicular to the frontal direction will enter both horns and be transmitted in phase.

From the foregoing it is seen that the 45 plane surface 17 plays an important part in establishing an impression of lateral direction by creating a maximum phase difference and a variation in intensity. Such an impression is more pronounced and is more 50 effective when the field of reception with both horns is limited. This is accomplished by converging the plane walls of opposite horns, the inclination or deviation from parallelism of each horn being substantially 5°. 45 For customary ranges this provision will give an exclusion in the off horn for sounds arriving greater than 5° from the center line of the two horns. In Fig. 4 the sound wave b is shown as being excluded from the horn 55 whereas it would be directed into the horn if the plane surface were not at an inclination.

Where the mouth section of the horn is 60 rectangular in cross-section for the reasons set forth the transition to curvilinear form 55 should not occur in the straight mouth section but rather at a point in the reverse curve section beyond the elbow, which point is approximately at the center of the total horn length.

60 I claim:

1. A receiver horn having an exponential variation of cross section with the length and an internal diameter at the small end between .625 and one inch.

65 2. A receiver horn, the area of whose cross

section is an exponential function of the distance from the small end, the rate of increase of the cross section being approximately six per cent for every two inches of length and the diameter of the small end being more 70 than two per cent of the diameter of the opening at the large end.

3. A receiver horn having an exponential variation of cross section with the length and an internal diameter at the small end more 75 than two per cent of the internal diameter at the large end.

4. A receiver horn, the area of the cross section of which is an exponential function of the distance from the small end, the diameter of the small end being greater than one-half of one per cent of the length of the horn, and the length of the horn being approximately equal to the wave length of the 80 lowest frequency of sound to be transmitted. 85

5. A receiver horn, the area of the cross section of which is an exponential function of the distance from the small end and the diameter of the small end being greater than one-half of one per cent of the length of the 90 horn.

6. A receiver horn, the area of the cross section of which is an exponential function of the distance from the small end and the length of the horn being approximately equal 95 to the wave length of the lowest frequency of sound to be transmitted.

7. A receiver horn having a cross section which is an exponential function of the distance from the small end and having a mouth 100 whose walls make an angle of approximately thirty degrees with the axis of the horn.

8. A receiver horn, the area of the cross section of which is an exponential function of the distance from the small end and the diameter of the large end being approximately 105 twenty-five per cent of the length of the horn.

9. A receiver horn having a cross section 110 area varying according to the equation $A = A_0 e^{mx}$ where m is given such a value as to make

$$\frac{A}{P} = \frac{L}{K}, \quad 115$$

L being the wave length of the lowest frequency to be received and K being a constant whose value lies between 3 and 4.

10. In a horn having an exponential variation of cross-section with the length, an elbow, the radius of the bend of the axis of the horn at the elbow being in length at least that of the trace of the plane containing the horn axis on any plane passed transversely 120 through the bend at right angles to the first mentioned plane.

11. In a sound receiving apparatus, a pair of parallel spaced horns mounted for movement in unison, the inner sides of the two 125 130

horns converging at an angle of approximately five degrees to a horn axis and the opposite side of each horn being flared.

12. In a sound receiving apparatus a pair of parallel horns having their axes separated by a distance not greater than the length of the longest sound wave to be received.
